DESIGN FOR A REMOTE CONTROLLER CASING

Lockwood Martling, Jr., Chicago, Ill., assignor to
Lloyd J. Andres, Itasca, Ill.

Application May 24, 1947, Serial No. 139,267

Term of patent 7 years

(Cl. D26—5)

To all whom it may concern:

Be it known that I, Lockwood Martling, Jr., a citizen of the United States and resident of Chicago, in the county of Cook and State of Illinois, have invented a new, original, and ornamental Design for Remote Controller Casing, of which the following is a specification, reference being had to the accompanying drawings, forming part thereof.

Fig. 1 is a perspective view of a remote controller casing, showing my new design;

Fig. 2 is a perspective rear view of the remote controller casing shown in Fig. 1;

The characteristic features of my design reside in the portions shown in full lines.

I claim:

The ornamental design for a remote controller casing, substantially as shown and described.

LOCKWOOD MARTLING, JR.
